DRILLING MACHINE

Frederic W. Hild, Los Angeles, Calif.

Original application February 2, 1921, Serial No. 441,768. Divided and this application January 30, 1930, Serial No. 424,563

24 Claims. (Cl. 255—19)

This application is a division of my application Serial No. 441,768, filed February 2, 1921.

This invention relates generally to drilling machines and more particularly to rotary drilling machines for sinking wells, wherein the feeding of the boring tool is automatically controlled.

An object of the invention is to provide a rotary drilling machine for drilling wells which is so designed that the drilling pressure may be automatically maintained at a substantially constant value.

Another object of the invention is to provide hydraulic means responsive to a portion of the weight of the drilling tool for automatically regulating the feeding movement of the tool.

A further object of the invention is to provide hydraulic means for indicating the conditions under which the drilling tool is operating.

The foregoing and other objects of the invention, which will be obvious upon reading the following specification, may be achieved by means of the apparatus illustrated in the accompanying drawing, in which the single figure is a view, partially in elevation and partially in section, of a drilling machine showing diagrammatically the means employed to automatically control the feeding of the drilling tool.

The illustrated drilling machine comprises the usual derrick 1 that is provided, at the top, with a crown block 2, from which is suspended a traveling block 3 by means of a cable 4 to constitute a multiple tackle that serves to support a drilling or cutting tool 5. The pull rope 6 of the multiple tackle is connected, as usual, to a windlass or hoist mechanism 7 for raising or lowering the drilling tool. The cutting tool 5, which is disposed to be fed by gravity, comprises a drill bit 8, attached to the lower end of a drill stem or pipe 9, which is provided, at its upper end, with a grief stem 11 of square or other suitable cross-section for effecting rotation of the drill bit.

In order that the drill may be suspended from the multiple tackle and also be free to rotate, the grief stem is provided, at its upper end, with a swivelled head 12 having a clevis 13 by means of which it is connected to the traveling block 3. As usual, the swivelled head 12 is provided with water-inlet openings 14 through which circulating water for the drill bit may be supplied in the conventional manner.

For rotating the drill stem 5, a power-driven rotary table 16 is provided and suitably mounted for rotation in a horizontal plane upon a base or foundation 17, centrally disposed within the derrick 1.

The rotary table 16 is provided with a central aperture of suitable shape and dimensions to loosely engage the grief stem 11 in such manner that it is free to move longitudinally through the aperture but is constrained to rotate with the table. As shown, the rotary table 16 has worm teeth 18 on its periphery which are engaged by a worm 19 that is disposed to be driven, by means of a belt and pulley connection 20, by an electric motor 21 or by any other suitable source of power.

When it is desired to lift the drilling tool 5, the hoist mechanism 7 may be operated by the motor 21 by means of a suitable belt-and-pulley connection 22. As shown, the hoist mechanism 7 comprises a winding drum 23 to which the end 6 of the cable or line 4 is connected in such manner that the cable 4 may be wound upon the drum 23 when it is actuated by the motor 21.

In order that the drill 5 may be lowered under control and may be retained in any predetermined position, the hoist drum or windlass 23 is provided with a suitable brake mechanism 24.

In the usual multiple tackle mechanism, an end 25 of the cable 4, which is not attached to the winding drum, is rigidly fixed to some portion of the derrick or to an anchor suitably fastened in the earth and is known as the dead end of the cable. However, in order to effect automatic operation of the feeding mechanism, the end 25 of the cable 4, which is normally fixed, is connected to a control mechanism which governs the feeding of the drill in accordance with the unsupported weight of the drill stem 5, which is obviously proportional to the pull exerted at the dead end 25 of the cable 4.

The feed-control mechanism comprises a fluid-tight cylinder 31, within which is disposed a cooperating piston 32 having a piston rod 33, to which the end 25 of cable 4 is connected. A body of liquid, such as oil or water, which is interposed between the piston 32 and the end of the cylinder 31, is subjected to a pressure that is proportional to the force exerted by the cable 4 and, consequently, is proportional to the weight or downward force exerted by that portion of the drill stem 5 which is not supported by the material that is being drilled.

In order to vary the feeding force of the drill inversely relative to the pressure exerted by it upon the work, the pressure set up within the fluid body in the cylinder 31 is transmitted, through a pipe 34, to a hydraulic regulating device 35 that is disposed to actuate the brake 24.

24 on the winding drum 23. As shown, the 5 hydraulic device 35 comprises a cylinder 36 that is provided with a piston 37 having a piston 10 rod 38 connected by means of linkage 39 to the 15 brake band 24. Beneath the piston 37 is disposed a strong coil spring 41 which normally 20 holds the brake band 24 in close engagement with the drum 23 to prevent it from rotating.

It may be readily understood that, when the 10 pressure exerted upon the operating liquid by the piston 32 is transmitted through the pipe 34 to the upper end of the cylinder 36, the 15 downward force exerted by the liquid upon the piston 37 will partially overcome the force exerted in the upward direction by the spring 41, and the brake band 24 will be loosened in proportion to the pressure within the fluid body. 20 Consequently, the retarding effect exerted upon the drum 23 by the brake 24 will be reduced, and the drum 23 will be permitted to turn an amount sufficient to loosen the cable 4 and permit the drill 5 to be lowered into the well which is being drilled by it.

During normal operation of the drilling machine, the pressure within the fluid body occupying the cylinders 31 and 36 is proportional to the weight of the drill stem 5 which is suspended by the multiple tackle and inversely proportional to the pressure exerted upon the 30 work by the drill bit 8. When, during the operation of drilling, the drill bit 8 cuts itself free, or, in other words, cuts away the material in such manner that it no longer exerts a substantial drilling pressure, the weight of the drill 35 stem, which is suspended by the tackle, will be increased, and the pressure in the hydraulic system, consequently, increased, whereby the 40 brake 24 will be released as described, and the drill will be permitted to move downwardly under the action of gravity, to such position that it will again exert the necessary drilling 45 pressure on the formation being drilled.

In order to provide for adjusting the rate of progress of the drill bit 8, the hydraulic device 45 is made adjustable by means of an adjusting screw 42. The adjusting screw 42 is disposed to exert a force against the lower end of the spring 41 in such manner that, when it is tightened, the spring 41 is caused to exert an increased pressure upon the brake band 24. It is 50 obvious that, if the pressure exerted upon the brake band 24 by the spring 41 is increased, then the pressure within the hydraulic system must necessarily be increased, in order to overcome the pressure exerted by the spring and to 55 release the brake 24. Consequently, if the spring 41 is tightened, the rate of drilling will be reduced and, conversely, if the spring is loosened, the rate of drilling will be increased, 60 inasmuch as the brake band 24 will not engage the drum 23 as closely as before, and the drilling tool 5 will be permitted to feed more rapidly under the action of gravity.

In order to indicate the pressure within the 65 hydraulic system, the connecting pipe 34 is provided with a pressure gauge 45 and, likewise, a pressure-regulating valve 46 is provided for regulating the hydraulic system and for preventing oscillations which might result from sudden variations in the drilling pressure, if the connecting pipe 34 were left open to permit free passage 70 of the liquid from the one to the other cylinder.

In considering the operation of a drilling machine embodying my invention, it will be noted 75 that the hydraulic system and the spring 41

provide a resilient support for the drill stem 5 and, should the drill bit 8 suddenly free itself from the material being drilled, it would quickly descend and re-engage the material by reason of the fact that the piston 32 in the cylinder 31 5 would move upwardly. The upward movement of the piston 32 would be permitted because of the resilience of the spring 41 and, inasmuch as the brake 24 would then be released to permit the drum 23 to turn slightly, the normal 10 operating conditions would be re-established and the piston 32 would return to its former position.

Although I have described a single embodiment of my invention, it will be obvious to those skilled in the art that various modifications 15 may be made in the disposition and proportions of the parts of the drilling machine without departing from the spirit and scope of the invention, as defined in the appended claims.

I claim as my invention:

1. In a well-drilling rig, the combination of a derrick, a drill stem, a line suspending the stem from the derrick, stem-feeding control means associated with the derrick and including a power drum having said line connected thereto, 25 whereby the drum may be rotated for lowering the stem, and secondary feeding control means for the stem including a hydraulic cylinder anchored adjacent to said drum and operatively connected to said line for controlling the movement of the line and permitting feeding of the stem downwardly by gravity, said latter means being separate from, and independent of, the 30 stem.

2. The combination, in a well-drilling apparatus, of a drill pipe, a lowering device for supporting a portion of the weight of the drill pipe, a brake associated with said device for controlling the feeding of the drill pipe, and resilient means operatively associated with said 35 device to actuate said brake as the portion of the weight of the drill pipe carried by said device varies.

3. In a drilling machine, a rotary drill tool disposed to be fed by gravity, means for suspending the drill tool, said suspending means containing a fluid-body under a pressure proportional to the force exerted on the suspending means by the drill tool, and means responsive to a pressure in the fluid body inversely 50 proportional to the force exerted by the tool on the suspending means for permitting the drill tool to be fed to its work by gravity.

4. The combination, in a well drilling apparatus, of a drill pipe, a lowering device for supporting a portion of the weight of the drill pipe, a hydraulic device associated with the lowering device and disposed to exert pressure in proportion to the portion of the weight of the drill pipe carried by said apparatus, a brake for controlling the lowering of the drill pipe, and means responsive to the pressure in the hydraulic device for actuating the brake.

5. In a well-drilling apparatus, in combination, a drill, a feeding device for supporting a portion of the weight of the drill, a mechanical brake associated with the feeding device for resisting downward movement of the drill, and means responsive to the force exerted by a predetermined portion of the weight of the drill 70 for releasing the brake.

6. In a well-drilling apparatus, in combination, a drill, means for rotating the drill, a feeding device for supporting a portion of the weight of the drill, said feeding device compris- 75

ing a brake disposed to resist downward movement of the drill, and a hydraulic device for releasing the brake in response to predetermined pressure exerted on the feeding device by the portion of the weight of the drill supported thereby.

7. In a drilling machine, a rotary and longitudinally-movable drill tool disposed to be fed by gravity, means containing a fluid body under pressure said pressure resulting from sustaining a portion of the weight of the tool by the fluid, means for resisting the feeding effect of gravity, and means responsive to the pressure in the fluid body for releasing the resisting means to permit the drill to advance at a rate substantially inversely proportional to the portion of the weight thereof which is sustained by the fluid body.

8. In a well-drilling apparatus, in combination, a rotatable drill, means for suspending the drill comprising a crown block and a traveling block, a cable passing through the blocks, a drum for winding the cable to raise or lower the drill, one end of said cable being connected thereto, a brake on said drum, a hydraulic cylinder, a piston within the cylinder operatively connected to the other end of the cable, and means responsive to the pressure within the cylinder for operating the brake on the drum.

9. In a well-drilling apparatus, in combination, a rotatable drill, a draw-works for hoisting the drill, means for suspending the drill comprising a cable and pulleys, one end of said cable being connected to the draw-works, a brake mechanism on the draw-works, a force-responsive device connected to the other end of the cable and disposed to actuate the brake on the draw-works to permit the drill to feed in accordance with the proportion of its weight which is not supported by the material being drilled.

10. In a well-drilling rig, in combination, a derrick, a drill stem, a line suspending the drill stem from the derrick, a power-operated drum having one end of the line connected thereto for raising said stem, a brake for controlling rotation of the drum, a hydraulic cylinder operatively connected to the other end of the line, and means associated with the hydraulic cylinder for operating the brake to permit lowering the drill stem.

11. The combination of a drilling means operative under its own weight for advancing, a brake for regulating the advance of said drilling means, and fluid-pressure means for automatically controlling said regulating brake in accordance with changes in the resistance of the material being drilled, to thereby maintain substantially uniform drilling conditions.

12. An apparatus for drilling deep wells comprising a drill stem, means for rotating the drill stem, means for suspending part of the weight of the drill stem and operable to pay out under the weight of the drill stem, a brake for regulating the action of said suspending means, and fluid-pressure means adapted to operate said brake in accordance with change in the resistance of the material being drilled.

13. The combination, in a well-drilling apparatus, of drilling means, a lowering device for supporting a portion of the weight of said drilling means, the drilling means carrying the remainder, braking means associated with said lowering device for controlling the feeding of the

drilling means, a fluid cylinder operatively associated with said lowering device so that variations in the weight carried thereby will cause variations of pressure within said cylinder, and a fluid cylinder controlled by said variations and operatively connected to said braking means to actuate the same.

14. In a drilling machine, a drill tool, means containing a fluid-body under pressure for supporting a portion of the weight of the tool by the pressure of the fluid, means for permitting the tool to be fed by gravity, and means actuated by variations in said fluid pressure as a result of the variations of the portion of the tool supported by the fluid to control the operation of said feeding means.

15. In a well drilling organization, a drill string provided with a boring tool, a cable providing a predetermined partial support for the string, winding means for said cable, means for securing said winding means, positive operating means for releasing said securing means, and means responsive to the tension in said cable for controlling said operating means whereby said operating means is caused to release said winding means so as to maintain a predetermined constant tension in said cable corresponding to said predetermined partial support for the drill string and thereby maintain a substantially constant pressure of the boring tool upon the earth formation.

16. In an apparatus of the character described, the combination with a drum, a brake for said drum, and a load-supporting cable on said drum, of an automatic brake actuator to which said cable and brake are operatively connected.

17. In an apparatus of the character described, the combination with a drum, a brake for said drum, a crown block, a traveling block adapted to be attached to a load and a cable extending from said drum and through said blocks, of an automatic brake actuator attached to the dead line of said cable and operatively connected to said brake.

18. In an apparatus of the character described, the combination with a drum, a brake for said drum, and a load-supporting cable on said drum, of an automatic brake actuator to which said cable and brake are connected, and a device interposed between said actuator and said brake, said device being manually movable to permit the operation of said brake independently of said actuator.

19. In combination with a drilling rig including drilling tools, a cable supporting said drilling tools, a revolvably mounted drum having said cable wound thereupon to effect lowering of said drilling tools when the drum is rotated to pay out cable, and releasable means for holding said drum against rotation; a drilling regulator comprising a translating device operatively connected to said cable and adapted to release said drum holding means, said translating device being actuated when the tension imposed upon said cable has increased to a predetermined maximum.

20. In combination with a drilling rig including drilling tools, a cable supporting said drilling tools, a revolvably mounted drum having said cable wound thereupon to effect lowering of said drilling tools when the drum is rotated to pay out cable, and releasable means for holding said drum against rotation; a drilling regulator comprising a translating device operatively connected to said cable and adapted to release or set

said drum holding means when the tension imposed upon said cable has increased to a predetermined maximum or decreased to a predetermined minimum respectively.

- 5 21. In combination with a drilling rig including drilling tools, a cable supporting said drilling tools, a revolvably mounted drum having said cable wound thereupon to effect lowering of said drilling tools when the drum is rotated 10 to pay out cable, and releasable means for holding said drum against rotation; a drilling regulator comprising a translating device operatively connected to said cable and adapted to release said drum holding means, said translating device being activated when the tension imposed 15 upon said cable has increased to a predetermined maximum, and means for adjusting said translating device to operate at selected points within the range of variation of cable stress.
22. In combination with a drilling rig including drilling tools, a cable supporting said drilling tools, a revolvably mounted drum having said cable wound thereupon to effect lowering of said 25 drilling tools when the drum is rotated to pay out cable, and releasable means for holding said drum against rotation; a drilling regulator comprising a translating device operatively connected to said cable and adapted to release or 30 set said drum holding means when the tension

imposed upon said cable has increased to a predetermined maximum or decreased to a predetermined minimum respectively, and means for adjusting said translating device to operate at selected points within the range of variation of cable stress.

23. In combination with a drilling rig including drilling tools, a cable supporting said drilling tools, means for paying out cable, and releasable means for holding said paying out 10 means inoperative, a drilling regulator comprising means operatively coupled to said cable and adapted to release said holding means, said releasing means being actuated when the tension imposed upon said cable exceeds a predetermined value.

24. In a device for automatically controlling the feeding pressure in a well-drilling apparatus, the combination of a lowering device having a cable wound thereon for supporting the drilling tool, a brake mechanism for controlling said lowering device, a fluid-pressure cylinder having a piston therein operatively connected to said brake mechanism to actuate the same, and means responsive to variations in the weight 25 carried by said cable for controlling the admission and release of fluid pressure to and from said cylinder.

FREDERIC W. HILD.
